(57) **CLAIM**

The ornamental design for a front bumper end cap for a vehicle, as shown and described.

DESCRIPTION

This application contains subject matter related to the following co-pending U.S. design patent application:
Application Ser. No. 29/509,784, filed Nov. 21, 2014 and entitled “Vehicle, Toy, and/or Replicas Thereof.”
FIG. 1 is a right front perspective view of a first embodiment of a front bumper end cap for a vehicle according to the design;

FIG. 2 is a front view thereof;

FIG. 3 is a right side view thereof;

FIG. 4 is a top view thereof; and

FIG. 5 is a bottom view thereof.

FIG. 6 is a left front perspective view of a second embodiment of the front bumper end cap for a vehicle according to the design;

FIG. 7 is a front view thereof;

FIG. 8 is a left side view thereof;

FIG. 9 is a top view thereof; and,

FIG. 10 is a bottom view thereof.

In the drawings, the broken lines depict environmental subject matter only and form no part of the claimed design.
